MECHANISM FOR FEEDING AND OPERATING UPON ARTICLES.

Application filed July 18, 1927. Serial No. 206,502.

This invention relates to machines of the type that are employed for rolling threads on bolt-blanks, although certain of the features embodied herein may well be capable 5 of use in machines used for other specific purposes. Therefore, while my invention is shown as applicable to, and actually employed in connection with, a machine of the type referred to, it is not intended thereby to 10 limit the improvements set forth hereinafter only to a machine of such particular type.

In machines that have been employed for the specific purpose mentioned, it has been proposed to deliver the headed bolt-blanks 15 automatically from a chute to and between a fixed die and a movable die, which cooperate to roll threads upon the shanks of such blanks and thereby to complete the bolts. However, such automatic feeding mechanisms have not 20 been generally satisfactory and, on that account, the blanks are usually delivered manually between the fixed and movable dies. One of the objects of my invention is to provide reliable and dependable feeding mechanism 25 which will insure the proper delivery of blanks or articles from a guide or chute to the dies or other mechanism adapted to operate thereon; also to provide an efficient construction of chute for delivering articles 30 therefrom to such dies or mechanism.

A further disadvantage which has attended the use of fixed and movable dies for rolling threads on articles such as bolt-blanks has been the failure of the bolts or articles to be 35 discharged from the dies after the threads have been rolled thereon, causing a bolt or article so treated to be brought back, with the movable die, into contact with other parts of the mechanism, causing injury thereto. 40 It is the further general object of my invention to provide, for machines of the general character described, means whereby, should a bolt or like article be so brought back by the movable die, the operation of the feeding mechanism will be automatically suspended, 45 and the article thus brought back may be conveniently removed without injury to the mechanism.

Further and more limited objects of the 50 invention will appear hereinafter, and all of the objects of the invention will be realized in and through the construction and arrangements of parts shown in the drawings hereof, wherein Fig. 1 represents a side elevation of 55 part of a machine adapted for rolling threads

on bolt-blanks and showing my invention applied thereto, in the form of an attachment to such machine; Fig. 2 a view similar to Fig. 1, looking from the opposite side of the machine, the cam-track slide being omitted; Fig. 60 3 a view similar to Fig. 1, showing the attachment in the position which it will assume when engaged by a bolt or other article which has not been discharged at the end of the forward movement of the movable die; Fig. 65 4 a plan view of Fig. 1, parts being broken away for the sake of clearness; Fig. 5 a rear elevation of the machine shown in Fig. 1, parts being omitted therefrom for the sake of clearness; Fig. 6 a sectional view taken on the line 6—6 of Fig. 1; Fig. 7 a vertical sectional view taken on the line 7—7 of Fig. 1; Fig. 8 an enlarged vertical sectional view taken at right angles to Fig. 7; Fig. 9 a horizontal sectional view taken on the line 9—9 of Fig. 75 8; Fig. 10 a sectional view on the line 10—10 of Fig. 8; Fig. 10^a a sectional view corresponding to the line x—x of Fig. 1; Fig. 11 a diagrammatic view showing the relative 80 positions of the stationary die, the movable die, and the pusher slide; and Figs. 12, 13 and 14 diagrammatic views showing the operation of the mechanism for delivering the bolt-blank or like article at the proper time 85 from the inclined chute to the vertical chute.

Describing the various parts shown herein by reference characters, A and A' denote the base of a machine such as is used for the purpose of rolling threads on bolts and similar articles. From the base A' there is suspended the fixed die A², the movable die A³ being slidable along the base member A and being carried by means of a cam slide which will be described hereinafter. The base member A carries mechanism, in the form of an attachment, for feeding and delivering the blanks to and between fixed and movable dies and for automatically suspending the operation of such feeding mechanism under the conditions pointed out hereinbefore. 90 The mechanism for feeding the blanks is carried by a base plate B having a machined seat B' at one end thereof and provided with horizontally spaced lugs B² to which the lower ends of parallel-rule links are pivoted, the upper ends of the links being pivoted to the base of a frame-casting C. These links are preferably made in pairs, each pair being connected by a cross brace B⁴ (see Fig. 5). This frame-casting is provided with a ma- 105 110

chined foot C' which is adapted to rest upon the seat B'.

For convenience of description, the left hand of the machine as shown in Figs. 1 and 5 3 will be assumed as the front and the opposite end as the rear, and the terms "front" and "rear" will be used hereinafter for the purpose of designating the relative positions of certain parts, but without any intention 10 thereby of limiting my invention to such specific location.

Bolted to the front of the frame-casting C is a vertical chute, indicated generally at D. This chute receives the headed blanks or 15 shanks, one at a time, from a downwardly and rearwardly inclined chute, indicated generally at E, and delivers them, one at a time, to and between the dies A², A³.

The vertical chute D will now be described 20 in detail.

The chute comprises a two-part upper section and a three-part lower section. The inner wall of the upper section D' (see Figs. 6 and 8), is rounded, except for the front end 25 thereof into which the rear end of the chute E projects, and the bore thus formed diminishes gradually in cross sectional area from the top to the bottom thereof. Pivoted to the front of the part D' and cooperating therewith to form the upper part of the chute, is a gate F, the pivotal support whereof is indicated at F'. This gate is provided with a slot in the front thereof to accommodate certain delivery portions of the chute E and 30 has secured to the lower portion thereof a block F² having an inverted frusto-conical surface F³ and a cylindrical surface F⁴ therebelow. The gate is normally held closed by means of a spring F⁵ secured at one end to 35 one side thereof and at its other end to a fixed point on the side of the chute D.

Within the upper portion of the bore of the chute section D' is a guide plate, indicated 40 generally at G. This plate has an upper flange G' by which it is fastened to the top of the rear of the chute, being provided below such flange with a downwardly and forwardly inclined portion G² from which the plate extends rearwardly and downwardly, 45 as shown at G³. The purpose of this plate will be explained hereinafter in connection with the details of the chute E.

The lower portion of the chute D comprises a fixed rear member D² having lateral recesses D³ (see Figs. 3, 7, 8 and 10^a) in which the sides of the front sections D⁵ are pivoted on vertical pins D⁴ each of such sections having a rearwardly extending arm D⁶. The sections D² and D⁵ are so shaped as to provide 55 a partially cylindrical bore in the upper portion thereof, with an inverted partially frusto-conical bore at the lower end thereof, the front edges of the sections D⁵ being spaced apart, as will appear clearly from Fig. 8. 60 The rear ends of the arms D⁶ cross each other,

and the angle between the crossing of the arms is in line with the roller H, which is carried by the pusher rod H', the front end H² of said pusher rod serving to push a bolt-blank, released from the chute D, between the dies A² and A³. Pusher rods for the purpose of pushing bolt-blanks between fixed and movable dies are old in machines of this general type. The front members D⁵ of the lower portion of the chute D are normally held in the positions shown in the drawings by means of plungers D⁷ mounted in the lower fixed section D² of the chute and pressed into engagement with the arms D⁶ by springs D⁸ (see Fig. 10^a). The arrangement of the pusher bar H' with reference to the fixed and movable dies A² and A³ is shown in Fig. 11.

The chute E is shown as composed of a pair of channeled plates secured together in spaced relation, with their flanges E' presented outwardly, forming therebetween a downwardly inclined passageway E² for the bolt-blanks. Secured to each upper flange is a wear plate E³ on which the heads of the bolt-blanks are adapted to rest as the blanks slide down the inclined chute E. In order to secure the channels of the chute E in spaced relation, one or more straps E⁴ may be secured to the bottom flanges of the said channels, the bottoms of the said straps being shown as bent downwardly, to permit the passage of a long bolt-blank thereabove. The channeled plates E constitute side plates for the inclined chute and each of these plates is thickened and widened at its lower end by means of a thick plate E⁵ bolted thereto, each of said plates E⁵ having a downwardly and forwardly inclined shoulder E⁶ adapted to engage a similar inclined surface D⁹ on one of the side members of the chute D. From 90 this shoulder, each of the plates E⁵ projects into the front of the upper chute section and is provided with a downwardly and forwardly inclined front edge E⁷ engaging a correspondingly shaped seat D¹⁰ in said chute section (see Figs. 1 and 6).

To facilitate the proper delivery of the blanks from the chute E² into the vertical chute D, the passage for the shanks at the lower or delivery end of the chute is contracted to approximately the diameters of the shanks by means of liner plates E⁸. These liner plates may be made of several sections, as indicated, the rearmost sections having their inner faces converging rearwardly. The inner ends of the liner plates project into the bore of the vertical part D' of the chute D, with their inner or rear ends beveled outwardly, as shown at E⁹, and such beveled ends also extending downwardly and rearwardly toward the rear wall of the chute section D (see Figs. 6 and 8). The purpose of the plate G and the particular construction 100 of the inner ends of the sides of the chute 105 110 115 120 125 130

E, as constituted by the rear ends of the plates E⁸, is to prevent the bolt-blanks delivered into the chute D from becoming inverted in or lodging across the said chute. 5 The blanks dislodged from the inclined chute are apt to rebound in the vertical chute and to become twisted or turned therein in such manner as to prevent them from being delivered freely, with their heads up, down the 10 chute D. By the construction shown herein, the head of a bolt-blank delivered from the chute E will strike the inclined surface G², and the shank of the blank will swing into engagement with the surface G³; the head of 15 the blank rebounds from such surface G² and strikes the downwardly and rearwardly inclined edges E⁹ of the plates E⁸, and the blank will be prevented by such plates and the rear wall of the upper part of the chute D from 20 being turned to such a position as to cause it to obstruct the said chute. In the event that the head of the bolt-blank should be thrown forwardly, after passing the surface E⁹, it will strike the downwardly inclined 25 surface F², thereby causing the blank to be straightened up before reaching the bottom of the lower part of the chute.

The side members of the chute E are provided, near their lower ends with slots E¹⁰, 30 E¹¹ and E¹² for the reception of the automatically operated arms for delivering the blanks one at a time, and at the proper time, from the inclined chute to the vertical chute. The construction and mode of operation of the 35 automatic bolt-feeding mechanism will now be described.

Bolted to a flange at the top of the frame-casting C is a bracket J carrying a journal sleeve J' in which is mounted a shaft K. The shaft projects forwardly beyond the end of the journal sleeve J' and has secured to its upper end a curved arm K' the lower end of which is adapted, by the rocking of the shaft K, to be projected through and withdrawn 40 from the aligned slots E¹⁰ in the channeled side members of the chute E, thereby serving, when in the space between said channeled plates, to hold the bolt-blanks thereabove against downward movement and, 45 when withdrawn, to permit the said blanks to move downwardly. Secured to the same shaft K is a curved arm K² which extends from the opposite side of said shaft and is adapted to be projected into and withdrawn 50 from the slots E¹¹ thereby to prevent the lower most bolt-blank in the chute E from being delivered into the chute D until the arm is withdrawn from the slots E¹¹. The arms K' and K² are so arranged that one of 55 these two arms will be projected across the inclined chute when the other is withdrawn, and vice versa; and the space between the slots E¹⁰ and E¹¹ is substantially equal to the diameter of the shank of a bolt-blank. A 60 spacing washer J² is interposed between the ends of the arms K' and K² which are keyed upon the shaft K. To facilitate the proper delivery into the chute D of the lowermost bolt-blank from its position between the slots E¹⁰ and E¹¹, the arm K' has secured thereto 70 a curved arm K³ the lower end of which is adapted to be projected into and through the slots E¹² when the arm K' is inserted into and through the slots E¹⁰ thereabove. The lower end of the arm K³ is beveled, as shown at K⁴, 75 whereby it will engage the upper surface of the lower part of the shank of the bolt-blank which is between the slots E¹⁰ and E¹¹ and add an ejecting action to the gravity feed of such blank, thereby insuring its delivery 80 into the upper portion of the chute D.

Keyed on the lower portion of the shaft K is a clutch collar K⁵; and interposed between the lower end of said clutch collar and a washer K⁶ is a spring K⁷, the said washer 85 being retained upon the shaft by means of nuts K⁸. The clutch collar K⁵ has a notch on each side of the upper end thereof and provided with a forwardly and downwardly beveled surface K⁹. Loosely mounted upon 90 the shaft K above the clutch collar K⁵ is a sleeve L, the said sleeve having two arms L' and L² projecting therefrom. A spring M is connected at one end to the arm L' and at 95 its opposite end to the frame-casting C. The arm L² is provided with the socket L³ of a ball-and-socket joint, the ball L⁴ being carried by the upper end of a longitudinally-extensible-and-contractible link L⁵, the lower end of which is provided with a ball L⁶ which 100 is seated within a socket N' in the upper intermediate part of a lever N, which lever has a downwardly and forwardly extending end N² provided with a roller N³, for a purpose to be described hereinafter. The rear end of the lever N is mounted on a stud shaft N⁴ (see Fig. 9), which is supported by a journal sleeve N⁵ bolted to the frame-casting C and carrying a journal N⁶ for a shaft O to which is rigidly secured an arm 105 O' having at its lower and forward end a roller O².

Projecting from the shaft O and rigid therewith is an arm O³, which arm is forked at its upper end, to receive therewithin a cross member P' on a sliding gate P which is adapted to be reciprocated across the bore of the chute D, being provided with an arcuate slot P² in the front end thereof (see Figs. 1, 3 and 9). The end of the shaft O which 110 is opposite the arm O' is supported by a block O⁴ carried by a part of the frame-casting C. Secured to the end of the shaft O beyond the block O⁴ is an arm O⁵, which arm has secured thereto one end of a spring O⁶, the opposite end of the spring being secured to an arm O' carried by the chute D.

Connected to and movable with the die A³ is a cam slide R, the said slide having an upper elevated track R' and a lower de- 115 120 125 130

pressed track R^2 connected by an inclined track R^3 . The rollers N^3 and O^2 are adapted to ride upon this track, normally being held in engagement therewith by the springs M and O^6 , respectively.

Secured to and projecting rearwardly from the rear pair of links B^3 is an arm S from the rear end of which is suspended a counter-weight S' , the counter-weight being such that, if the mechanism supported by the frame-casting C in front thereof be moved a short distance rearwardly, the counter-weight will of itself complete the lifting of such mechanism upon the links B^3 , thereby lifting the rollers N^3 and O^2 from engagement with the upper track R' , as indicated in Fig. 3.

With the parts constructed and arranged in the manner described herein, the operation will be as follows:

26 Bolt-blanks are inserted within the chute E with their heads resting upon the wear plates E^3 and the shanks extending downwardly. It will be assumed that the arms K' , K^2 and K^3 are in the positions shown in Figs. 1 and 10, wherein the arm K^2 blocks the delivery of the bolts to the chute D therebelow, the arm K' being withdrawn from the slots E^{11} and the arm K^3 from the slots K^{12} .

30 The slide R will be moved rearwardly until the roller N^3 rides off the upper track R' onto the lower track R^2 . This enables the spring M to rock the shaft K , through the clutch members L and K^5 , withdrawing the arm K^2 and simultaneously inserting the arms K' and K^3 across the chute D . The arm K' will hold the stack of bolt-blanks thereabove from moving downwardly along the guide constituted by the chute E , but the arm K^2 , being withdrawn, will allow the lowermost bolt-blank to slide down into the chute D , the movement of said bolt being accelerated by the beveled end of the arm K^3 . The bolt-blank so discharged will be delivered with its lower end resting on top of the slide P which meanwhile has been moved forwardly by the action of the spring O^6 and arms O^2 and O^5 when the roller O^2 rides off the track R' onto the lower track R^2 .

35 On the reverse movement of the slide R , the rollers N^3 and O^2 ride upon the upper track R' . The roller N^3 elevates the arm N and, the arm L^5 rocks the shaft K through the clutch members L and K^5 , thereby withdrawing the arms K' and K^3 from the chute D and at the same time inserting the arm K^2 therein. This will enable the stack of bolt-blanks to move one step downwardly, with the lowermost bolt-blank held in the lowermost position in the chute E by the arm K^2 . 40 While this action is taking place, the roller O^2 will have been lifted, rocking the shaft O and moving the slide P rearwardly, thereby permitting the bolt-blank that was resting thereon to drop into the lower portion of the vertical chute, with its head in the tapered

lower end of the chute. When the bolt is in this position, the movable die A^3 and the fixed die A^2 are in approximately the positions shown in Fig. 11, wherein the end H^2 of the pusher bar is about to engage the bolt-blank and push it upon the rear end of the fixed die so as to insure the proper gripping of the blank between the fixed and movable dies. The parts are so arranged that the roller H will engage the front crossed ends of the arms D^6 in time to rock the front lower chute sections D^5 apart and permit the bolt-blank hanging therefrom to be moved outwardly and forwardly by the end of the pusher bar.

80 Should a bolt blank be caught between the upper and the lower chute sections, the sliding gate P , as it moves forward, will engage said bolt and push the same forward, together with the swinging gate F , discharging the blank through the front opening in the chute.

85 As pointed out hereinbefore, it happens sometimes that a bolt blank inserted between the fixed and movable dies is not disengaged and delivered therefrom at the end of the forward thread-rolling movement of the movable die. When this occurs, such a bolt will be carried rearwardly by the movable die into engagement with the mechanism, thereby endangering the latter. To prevent injury to the mechanism by such action, the said mechanism is supported from the base A on the links B^3 . Should a bolt be carried rearwardly and strike the lower portion of the vertical chute, the impact of the bolt will cause the frame-casting C and the parts attached to be moved upwardly and rearwardly, this action being facilitated by the counter-weight S' . This will result in lifting the rollers O^2 and N^3 above the upper track R' and 90 will prevent the operation of the bolt-feeding and delivering mechanism until such time as the defective bolt shall have been removed and the parts restored to the normal working position indicated in Fig. 1.

95 Should the movement of any of the arms K' , K^2 , or K^3 across the chute E be opposed unduly, as by encountering a blank which is hung up in the chute, this opposition to or stoppage of the movement of such arm will cause the clutch sleeve K^5 to be moved rearwardly by the engagement of the appropriate projection L^7 on the sleeve L with its corresponding inclined surface K^6 , thus breaking the driving connection between such arm and the shaft K and preventing injury to the mechanism for delivering the bolt-blanks to the chute D .

100 As is well known to those skilled in the art to which this invention relates, the movable die A^3 and the pusher bar will be operated from a common shaft, as by means of cranks.

Having thus described my invention, what I claim is:—

105 1. The combination, with a guide along 130

- which articles are moved, of mechanism for operating upon the articles delivered from the said guide, and means for delivering the articles successively to such operating mechanism, such delivering means comprising a pair of arms spaced apart in the direction of the length of the said guide, and means for projecting the said arms transversely alternately across the said guide and into and out of the path of movement of the articles therealong, whereby one of said arms serves to retain the series of articles therebeyond against movement when the other of said arms is withdrawn from the guide to permit the delivery 15 of an article from said guide and whereby, on reverse movement of said arms, the second arm will be brought into the path of movement of said articles and the first arm will be withdrawn from such path of movement, and 20 means movable by and with the first arm and adapted to be projected across the said guide to engage an article between the said arms thereby to facilitate the discharge of such article from the guide when the second 25 arm is withdrawn therefrom.
2. The combination, with a guide along which articles are moved, of mechanism for operating upon the articles delivered from the said guide, means for delivering articles 30 successively from said guide to such operating mechanism, the said means comprising a rock shaft extending in the direction of the length of said guide, a pair of arms secured to said shaft and spaced apart thereon and 35 adapted, by the rocking of said shaft, to be projected transversely of said guide and alternately into and out of the path of movement of the articles along said guide, and connections between said operating 40 means and the said shaft for rocking the latter through the movements of such operating means.
3. The combination, with a guide along which articles are moved, of mechanism for 45 operating upon the articles delivered from the said guide, and means for delivering articles successively from said guide to such operating means, the said means comprising a rock shaft extending in the direction of the 50 length of said guide, a pair of arms secured to said shaft and spaced apart thereon and adapted, by the rocking of said shaft, to be projected transversely of said guide and alternately into and out of the path of movement 55 of the articles along said guide.
4. The combination, with a guide along which articles are moved, of means for delivering the articles successively from the said guide, the said means comprising a pair of members spaced apart in the direction of the length of said guide and adapted to be projected transversely of said guide and alternately into and out of the path of movement of the articles along said guide, and 60 means also adapted to be projected into and out of such path of movement and between the said members for engaging an article adjacent to the delivery end of said guide and moving the same positively toward such end when the member adjacent to the delivery 65 end of said guide is moved out of such path of movement.
5. The combination, with a guide along which articles are moved, of reciprocatory means for operating upon the articles as they are delivered successively from said guide, and means for so delivering the articles successively from the said guide, the said means comprising a shaft extending in the direction of the length of said guide, a pair of arms secured to said shaft and spaced apart thereon and adapted, by the rocking of said shaft, to be projected transversely of said guide and alternately into and out of the path of movement of the articles along said 70 guide, and connections between said shaft and said reciprocatory means for rocking the shaft, thereby to deliver the articles successively from the guide in accordance with the requirements of the operating mechanism, 75 the means for rocking the shaft comprising a clutch adapted to break the driving connection between the shaft and the rocking means through abnormal resistance to the movement of either of the said arms.
6. The combination, with a downwardly inclined chute for articles in the form of headed shanks adapted to support the said articles by the heads thereof with their shanks extending downwardly into said chute as 80 they move therealong, of means for operating upon the articles delivered from the lower end of said chute, and means for delivering the articles, one at a time, to such operating mechanism, such delivering means comprising a pair of arms spaced apart in the direction of the length of the said chute, and means for projecting the said arms alternately across the said chute and into and out of the path of movement of the articles therealong, whereby the upper of said arms serves to retain the series of articles thereabove against movement when the lower of said arms is withdrawn from the chute to permit the delivery of an article from the lower end 85 of said chute and whereby, on the reverse movement of said arms, the lower arm will be brought into the path of movement of said articles and the upper arm will be withdrawn from such path of movement, and means movable with the upper arm and adapted to be projected across the said chute to engage the body of an article below such upper arm, thereby to facilitate the discharge of such article from the chute when the lower 90 arm is withdrawn therefrom.
7. In a machine for operating on elongated blanks, the combination, with such operating mechanism, of a guide along which such blanks are moved, a vertical chute interposed 95

between the delivery end of the guide and such operating mechanism, and means for delivering the blanks successively from the guide to the vertical chute, the vertical chute having on the front and rear walls thereof cooperating downwardly inclined vertically spaced surfaces against which the blanks are adapted to strike as they are delivered successively from the guide, thereby to facilitate and control the delivery of the blanks down the said vertical chute.

8. In a machine for operating on headed shanks, the combination, with such operating mechanism, of a downwardly inclined chute adapted to receive such articles and to support them by their heads as they are fed therewith, of a vertical chute interposed between the lower end of the former chute and such operating mechanism, means for delivering the articles successively from the inclined chute to the vertical chute, and an aligning plate in the upper rear portion of the vertical chute having a forwardly and downwardly inclined surface against which the heads of the shanks are adapted to strike as they are delivered successively from the inclined chute thereby to facilitate and control the delivery of the articles down the said vertical chute.

9. In a machine for operating on headed shanks, the combination, with such operating mechanism, of a downwardly inclined chute adapted to receive such articles and to support them by their heads as they are fed therewith, of a vertical chute interposed between the lower end of the former chute and such operating mechanism, and means for delivering the articles successively from the inclined chute to the vertical chute, and an aligning plate in the upper rear portion of the vertical chute having a forwardly and downwardly inclined surface against which the heads of the shanks are adapted to strike as they are delivered successively from the inclined chute, said plate also having a downwardly and rearwardly inclined surface below the first mentioned surface adapted to engage the shanks of said articles thereby to align the articles in said chute.

10. In a machine for operating on headed shanks, the combination, with such operating mechanism, of a downwardly inclined chute adapted to receive such articles and to support them by their heads as they are fed therewith, of a vertical chute interposed between the lower end of the former chute and such operating mechanism, and means for delivering the articles successively from the inclined chute to the vertical chute, the vertical chute having on the rear wall thereof a forwardly and downwardly inclined surface against which the heads of the shanks are adapted to strike as they are delivered successively from the inclined chute, there being a downwardly and rearwardly inclined surface extending from the first mentioned surface, and coop-

erating downwardly and rearwardly inclined guides projecting into the forward side of the vertical chute, the said surfaces and guides cooperating to ensure the delivery of the articles vertically along the second chute.

11. In a machine for operating on elongated articles, the combination, with such operating mechanism, of a vertical chute for delivering such articles successively to such mechanism, a slide movable transversely of said chute and having a slot in one end thereof adapted to be brought into and out of register with the bore of said chute, connections for reciprocating said slide through such operating mechanism, and means for delivering such articles successively into the vertical chute above said slide, the said chute having a yieldably-supported section facing said slot.

12. In a machine for operating on elongated articles, the combination, with such operating mechanism, of a vertical chute for delivering such articles successively to such mechanism, a slide movable transversely of said chute and adapted alternately to open and close the bore of said chute, connections for operating said slide through such operating mechanism, means for delivering articles successively into the chute above said slide, the said chute having a gate in the wall thereof opposed to the end of the slide which moves across said chute, the said gate being pivoted at one end, and means yieldingly holding the said gate in closed position.

13. In a machine for operating on headed shanks, the combination, with such operating mechanism, of a vertical chute for delivering articles successively to such operating mechanism, the said chute comprising an upper portion to which the shanks are delivered in a vertical position, with a slide movable across the bottom of such upper portion and connected with such operating mechanism for delivering the shanks successively from the upper to the lower portion of said chute, a swinging gate in the wall of the upper part of the chute which is opposed to the end of said slide which moves across said chute, and means yieldingly holding said gate in closed position, the said gate having a downwardly and inwardly inclined portion adapted to assist in delivering articles vertically from the upper portion to the lower portion of said chute.

14. In a machine for operating upon elongated articles, the combination, with such operating mechanism and means for reciprocating the same, of a vertical chute, a slide movable transversely of said chute and dividing the same into an upper and a lower section and adapted to permit the blanks successively to drop from the upper to the lower chute section, connections between said slide and the said reciprocating means, the lower section of the chute comprising a pair of mov-

able members adapted to receive an article from the portion of the chute thereabove and to support the article in position to be removed therefrom by the operating mechanism, and means operated by the said reciprocating means for moving said members thereby to permit the removal of an article therefrom.

15. In a machine for operating upon elongated articles, the combination, with such operating mechanism and means for reciprocating the same, of a vertical chute for delivering articles, successively, to such mechanism, the said vertical chute comprising a pair of chute members each pivoted for movement about a vertical axis and each having an operating arm extending therefrom, the arms being crossed and the said chute members adapted to temporarily retain an article therein, means normally holding the said chute members in their closed position, and means for engaging the crossed arms thereby to rock the chute members about their pivots and permit the release of an article therefrom.

25. 16. In a machine for operating upon elongated articles, the combination, with such operating mechanism and means for reciprocating the same, of a vertical chute for delivering articles, successively, to such mechanism, the said vertical chute comprising a pair of relatively movable chute members adapted to temporarily retain an article therein, means normally holding the said chute members in their relatively closed position, and means operated by the said reciprocating means for separating the chute members against the action of such closing means thereby to permit the release of an article therefrom.

17. In a machine for operating upon headed shanks, the combination, with such operating mechanism and means for reciprocating the same, of a vertical chute above said mechanism comprising a pair of chute members jointly forming at their bottom a seat for supporting a shank by the head thereof with the shank projecting below said chute, each of said members being mounted for rotation about a vertical pivot and having their front ends spaced apart and each having a rearwardly extending arm, the said arms being crossed, and means operated by said reciprocating means for engaging the crossed portions of said arms thereby to rock the chute members apart and enable an article supported thereby to be released and delivered to such operating mechanism.

18. In a machine for rolling threads upon bolt-blanks, the combination, with a fixed die and a reciprocable die between which the blanks are adapted to be engaged for rolling threads thereon, of mechanism for delivering bolt-blanks successively to and between said dies, and operating connections between said reciprocable die and such delivering mechanism, the said connections being adapted to

be broken by the engagement of a bolt with such mechanism, due to the return movement of the reciprocable die.

19. The combination, with a pair of relatively movable dies, of mechanism for delivering articles successively to and between said dies, and operating connections between a movable die and such delivering mechanism, the said connections being adapted to be broken by the engagement of an article with such mechanism, due to the movement of the last-mentioned die toward such mechanism.

20. In a machine for rolling threads upon bolt-blanks, the combination, with a fixed die and a reciprocable die between which the blanks are adapted to be engaged for rolling threads thereon, of a vertical chute, an inclined chute, mechanism for delivering bolt-blanks successively from the inclined chute to the vertical chute, mechanism for delivering blanks, successively, from the vertical chute to and between the said dies, connections between such reciprocable die and the blank-feeding and delivering mechanism for operating such mechanism, and means for breaking such connection, the breaking means being operable by the engagement of a bolt with such mechanism, due to the return movement of the movable die.

21. The combination, with a pair of relatively movable dies, of a vertical chute, a guide, mechanism for delivering articles successively from the guide to the vertical chute, mechanism for delivering blanks successively from the vertical chute to and between the said dies, connections between a movable die and the article-delivering mechanism for operating such mechanism, and means for breaking such connection, the breaking means being operated by the engagement of an article with such mechanism, due to the movement of the movable die toward such mechanism.

22. In a machine for rolling threads upon bolt-blanks, the combination, with a fixed die and a movable die between which the blanks are adapted to be engaged for rolling threads thereon, of roller-operated mechanism for delivering bolt-blanks successively to and between the said dies, a slide having an upper track and a lower track for engagement with such roller, and means operative by the engagement of a bolt with such mechanism, due to the return movement of the movable die, for lifting the said roller out of engagement with the said slide.

23. The combination, with a pair of relatively movable dies between which blanks are adapted to be engaged, of a vertical chute, an inclined chute, roller-operated mechanism for delivering blanks successively from the inclined chute to the vertical chute, roller-operated mechanism for delivering blanks successively from the vertical chute to and between the said dies, a slide connected with

and movable with the movable die, the said slide having an upper track and a lower track for engagement with said rollers, and means operative by the engagement of a blank with such mechanism, due to the movement of such movable die toward such mechanism, for lifting the said rollers out of engagement with the said slide.

24. In a machine for rolling threads upon bolt-blanks, the combination, with a fixed die and a reciprocable die between which the blanks are adapted to be engaged for rolling threads thereon, of a member reciprocable with said die, a frame, mechanism carried by said frame for delivering bolt-blanks successively to and between the said dies, means carried by said frame and normally operative by the movement of the said member for operating the blank delivering mechanism, and means operative by a bolt retained between said dies during the return movement of the reciprocable die, for lifting the said frame and the attached mechanism out of engagement with such reciprocable member.

25. The combination, with a fixed and a reciprocable die, of mechanism for delivering articles successively to and between the said dies and means operative by an article retained between said dies during the return movement of such reciprocable die, for suspending the operation of such delivering mechanism.

26. In a machine for rolling threads upon bolt-blanks, the combination, with a fixed die

and a reciprocable die between which the blanks are adapted to be engaged for rolling threads thereon, of mechanism for feeding and delivering bolt-blanks successively to and between the said dies, a reciprocatory member movable with the reciprocable die for engaging and operating the said mechanism, a frame supporting the said mechanism, parallel-rule links supporting said frame, a counter-balance for said frame and the attached mechanism, and means operative by a bolt retained between said dies during the reverse movement of the reciprocable die, for imparting a lifting movement to said mechanism and frame, thereby to break the driving connection between the reciprocatory member and the said mechanism.

27. The combination, with a fixed die and a reciprocable die between which articles are adapted to be engaged, of mechanism for delivering said articles successively to and between the said dies, means movable with such reciprocable die for operating the said mechanism, parallel-rule links supporting said mechanism, and means operative by an article retained between said dies during the return movement of such reciprocable die for imparting a lifting movement to said mechanism upon said links, thereby to break the driving connection between the said mechanism and its operating means.

In testimony whereof, I hereunto affix my signature.

CHARLES F. NEWPHER.
